INDUCTION HEATING HEAD

Howard E. Somes, Detroit, Mich., assignor to Budd
Induction Heating, Inc., Philadelphia, Pa., a
corporation of Michigan

Application February 6, 1945, Serial No. 576,411

6 Claims. (Cl. 219—13)

This invention relates to induction heating heads, particularly to induction heating heads of the character utilized for electro-magnetically inducing high frequency heating currents in the surface of an article to be heat treated.

In the case of articles having one or more circumferential grooves, such as for example, an article having a ball bearing race which is desired to be hardened, it has been the practice to use a heating head having helical coil which was disposed coaxially with respect to the article. In such cases, it was not possible, due to the variable spacing of the groove bottom from the coil, to heat the groove surface to a uniform depth. This gave undesirable, non-uniform distribution of the residual stresses which resulted from the heat treating operation.

The object of the present invention is to provide an induction heating head of improved construction by means of which the head and the article to be heat treated can be disposed one within the other in such relation that circumferential grooves in the article can be heated to a uniform depth during relative rotation of the head and the article.

Another object is to provide an induction heating head with a coil having eccentric projecting portions backed up by a magnetic core which extends only for the circumferential extent of the eccentric portions.

With the above and other objects in view which will be apparent from the following detailed description to those skilled in the art to which the invention appertains, the present invention consists in certain features of construction and combinations of parts to be hereinafter described with reference to the accompanying drawings, and then claimed.

In the drawings which illustrate a suitable embodiment of the invention:

Figure 1 is a vertical section taken through the induction heating head and showing the same in operative relation with an internally grooved workpiece;

Figure 2 is a transverse section taken approximately on line 2—2 of Figure 1;

Figure 3 is a section taken approximately on line 3—3 of Figure 1; and

Figure 4 is a side elevation of the heating head shown in Figure 1.

Referring to the accompanying drawings in which like numerals refer to like parts throughout the several views, the heating head of the present invention is of the character adapted to be supported by a current conducting arbor.

The heating head is comprised of a support 1, a core 2 and a coil 3. The support 1 is of annular formation and provided with a semi-circular recess 4 extending throughout the length thereof, and within this recess adjacent the lower end thereof, as viewed in Figure 1, with a semi-circular groove 5 which receives an arcuate element 6 having an angular upwardly extending projection 7.

10 The core 2 is comprised of a plurality of tapered laminations of high magnetic permeability seated against the bottom of the recess 4 and having notched portions 8 engaged or interlocked with the projection 7. The laminated core 2 is formed with a side opening window 9, and the support is recessed to provide a shoulder 10 at its lower end, the bottom 11 of this recess being circumferentially continuous with the bottom of the window 9. The surface 11 and the bottom of the window 9 is provided with an insulated covering 12 which is surrounded by the coil 3, the turns of the coil being insulated from each other.

15 Associated with the upper end of the laminated core 2 is an arcuate element 13 having a portion 14 fitting into notches in the upper end of the core laminations, and surrounding the support 1 is an annular shouldered ring 15 engaged with the element 13 and an upper end shouldered portion 16 of the support 1. This ring is held in 20 clamping position against the element 13 and shoulder 16 by a nut 17 threaded onto the support 1.

25 The upper end 18 of the coil 3 is provided with an angle fitting 19. The lower end 20 of the coil 3 is inwardly turned to fit within an opening 21 formed within the support 1 adjacent the lower end thereof as shown in broken outline in Figures 1 and 2.

30 The coil 3 is provided with a cooling fluid passage 22 which at the lower end communicates through an aperture 23 with an annular recess 24 formed in the lower end of the support 1. The annular recess 24 is closed in by a suitable closure plate 25. Extending upwardly from the 35 annular recess 24 and through the upper end of the support 1 is a passage 26 having a tubular connector fitting 27 threaded thereinto.

40 The upper end of the support 1 is provided with an insulating ring 28 and bearing against the insulating ring 28 is a passaged member 29 into which the fitting 19 is positioned. In practice the support 1 is carried at one end of one conductor of an arbor (not shown), the member 29 being carried by a clamping ring 30 which is clamped 45 about an outer conductor of the arbor. Cooling

fluid is introduced into the member 29 and flows through the coil 3, thence through the annular passage 24 and is discharged through passage-way 26.

The coil turns, at the portions opposite the core 2, are angularly offset as at 31 so that the turns, except for the offsets 31, are parallel to each other and to a plane intersecting the axis of the coil.

In accordance with the present invention the coil turns are each provided with a transversely projecting portion 32 at the one side which are truly cylindrical for a portion of their extent and then gradually merge into the faces of the coil turns at about the terminations of the core 2. The diameter of the projecting portions 32 is substantially the same as the diameter of the internal grooves 33 of the tubular article 34 to be heat treated. The cross sectional contour of the projections 32 corresponds substantially to the cross sectional contour of the grooves 33. It is to be understood, of course, that the projections 32 correspond in number and axial spacing to the grooves to be heated and that if only one groove is to be heated, there will be only one such projection.

The projections 32 may be an integral part of the coil turns or if desired they may be separate elements suitably secured to the outer faces of the coil turns. The maximum transverse dimension of the head through the projections is such that in practice the head can be disposed within the article 34. In practice, as set forth in my concurrently filed application Serial No. 576,410, the head after being positioned within the article, is shifted so that its axis coincides with the axis of the projections 32 and to enter the projections within the grooves 33 while maintaining slight clearance with the bottoms of the grooves. The head is then rapidly rotated about the axis of the projections with the result that upon energization of the coil the current flowing through the projections in cooperation with the semi-circular core 2 and during rotation of the head will induce heating currents in the surfaces of the grooves 33.

As a result of the semi-circular core 2, only those portions of the coil turns which are provided with the projections 32 induce heating currents in the article.

By conforming the cross sectional contour of the projections substantially to that of the grooves, the groove surfaces are heated to a uniform depth with the result that after quenching, residual stresses resulting from the heat treating operation will be uniformly distributed.

It is to be understood that formal changes may be made in the detailed construction and arrangement of the parts described without departing from the spirit and substance of the invention, the scope of which is defined by the appended claims.

What is claimed is:

1. An induction heating head comprising a cylindrical support, a current conducting coil surrounding said support, and a magnetic core between said support and said coil for a portion only of the circumference of said support, at least

one of the turns of said coil substantially for the extent of said core having a radially outwardly projecting portion, said one turn for the extent of said projecting portion being parallel to a plane transversely intersecting the axis of said coil.

2. An induction heating head comprising a cylindrical support, a current conducting coil surrounding said support, and a magnetic core between said support and said coil for a portion only of the circumference of said support, at least one of the turns of said coil substantially for the extent of said core having a radially outwardly projecting portion, said one turn for the extent of said projecting portion being parallel to a plane transversely intersecting the axis of said coil, said coil being insulated from said core and said support.

3. An induction heating head comprising a cylindrical support having an arcuate recess in the peripheral surface thereof extending for a portion only of the circumferential extent thereof, an arcuate core seated in said recess, and a current conducting coil surrounding and being insulated from said core and coil, at least one of the turns of said coil being parallel to a plane transversely intersecting the axis of said coil, said one turn having a radially outwardly projecting portion extending circumferentially for substantially the circumferential extent of said core.

4. An induction heating head comprising a support, a current conducting coil carried by said support, and an arcuate magnetic core adjacent the internal surface of said coil, said core extending for approximately one-half the periphery of said coil, at least one of the turns of said coil for the extent of said core being parallel to a plane transversely intersecting the axis of said coil and for said extent having a portion extending radially outwardly from the outer surface thereof.

5. An induction heating head comprising a support, a current conducting coil carried by said support, and an arcuate magnetic core adjacent the internal surface of said coil, said core extending for approximately one-half the periphery of said coil, at least one of the turns of said coil for the extent of said core being parallel to a plane transversely intersecting the axis of said coil and for said extent having a portion extending radially outwardly from the outer surface thereof, said outwardly extending portion having a cylindrical surface intermediate its ends and gradually merging at its ends into the surface of said turn.

6. An induction heating head comprising a cylindrical support having an arcuate recess in the external surface thereof, said recess extending for a portion only of the circumference of said support, a radially laminated magnetic core seated in said recess, means locking said core in said recess, and a coil surrounding said support and core, at least one of the turns of said coil having an eccentric outwardly extending portion, said eccentric portion being substantially coextensive with said core.

HOWARD E. SOMES.
